CRATE FOR MILK CONTAINERS OR THE LIKE

Houston Rehrig, Pasadena, and Richard F. Gildart, Montebello, Calif., assignors to Rehrig Pacific Company, Los Angeles, Calif., a corporation of California

Filed Sept. 1, 1966, Ser. No. 3,688

Term of patent 14 years

(Cl. D58—5)

FIG. 2

FIG. 1 is a front perspective view of a crate for milk containers or the like showing our new design; and

FIG. 2 is a side elevational view thereof on an enlarged scale, the other sides being identical thereto.

The bottom of the crate for milk containers or the like is substantially plain and unornamented.

We claim:

The ornamental design for a crate for milk containers or the like, substantially as shown and described.
